United States Patent Office

Des. 231,208
Patented Apr. 9, 1974

231,208

AIRCRAFT

Robert H. Drinon, Kent, and Gottfried O. Friebel, Bellevue, Wash., and Antonino Di Blasi, Naples, and Alfredo Capuani, Turin, Italy, assignors to The Boeing Company, Seattle, Wash., and Aeritalia S.p.A., Naples, Italy

Filed Mar. 31, 1972, Ser. No. 240,326

Term of patent 14 years

Int. Cl. D12—07
U.S. Cl. D12—80

Fig. 1

Fig. 2

FIG. 1 is a side elevational view of an aircraft showing our new design;

FIG. 2 is a front elevational view; and

FIG. 3 is a top plan view thereof.

The broken line disclosure of landing gear is for illustrative purposes only.

We claim:

The ornamental design for an aircraft, as shown and described.
